SUCTION PRESS ROLL AND METHOD FOR MANUFACTURING SAME

James E. Post, South Duxbury, Mass.
(62-B Byrne Court, Wayne, N.J. 07470)
Filed Apr. 19, 1965, Ser. No. 449,035
3 Claims. (Cl. 162—372)

ABSTRACT OF THE DISCLOSURE

A suction press roll including a perforated metal roll to which is secured a resilient material having smooth surfaced holes extending radially therethrough which are in alignment with the perforations in the metal roll. The holes can be of substantially uniform diameter or provided with a flared portion adjacent to the metal roll. The suction press roll is produced by covering a perforated metal roll with a predetermined thickness of a resilient material in an uncured state, curing the resilient material to a predetermined hardness in the presence of smooth surfaced elongated inserts of suitable configuration which extend radially through the resilient material covering and into the metal roll perforations and then removing the inserts.

This invention relates to the extraction of liquid from a rapidly moving web or sheet and more particularly, to suction rolls useful, for example, in paper making machines for extracting water from a web of pulp or paper and to a method for making such rolls.

A principal object of the present invention is to provide improved suction rolls for the more efficient and economical removal of a liquid such as water from a rapidly moving web or sheet of material such as paper.

Another object of the invention is to provide improved suction rolls comprising a perforated metal cylinder or roll covered with a layer of resilient material having holes or perforations extending radially therethrough which possess very smooth surfaces or walls.

Still another object of the invention is to provide improved suction rolls comprising a perforated metal roll surfaced with a resilient material having very smooth surfaced holes or perforations extending radially therethrough which are in alignment with the perforations in the metal roll, the holes in said resilient material being of substantially uniform diameter therethrough.

Still another object of the invention is to provide improved suction rolls comprising a perforated metal roll or shell to which is bonded or otherwise secured to the outer diameter thereof a covering of a resilient material such as rubber having very smooth surfaced holes extending radially therethrough, the portion or end of the holes adjacent to the roll being flared.

A further object of the invention is to provide a suction press roll comprising a stationary suction box and a perforated rotatable metal roll or shell surrounding the suction box covered with a resilient material having holes as heretofore noted.

A still further object of the invention is to provide a method for producing suction rolls of the above constructions.

Other objects of the invention will in part be obvious and will in part appear hereinafter.

The invention accordingly comprises the method involving the several steps and the relation and the order of one or more of such steps with respect to each of the others, and the apparatus possessing the construction, combination of elements and arrangement of parts which are exemplified in the following detailed disclosure and the scope of the application of which will be indicated in the claims.

2

For a fuller understanding of the nature and objects of the invention reference should be had to the following detailed description taken in connection with the accompanying drawings wherein:

5 FIGURE 1 is an exaggerated fragmentary sectional view of a perforated metal roll covered with a resilient material such as rubber illustrating one embodiment of the present invention for providing smooth surfaced, radially extending holes through the resilient material covering;

10 FIGURES 2 and 3 illustrate inserts or pegs which may be used in providing holes of the type shown in FIGURE 1;

15 FIGURE 4 is an exaggerated fragmentary sectional view of a perforated metal roll covered with a resilient material illustrating the formation of one preferred type of telescope-like hole in the resilient material;

20 FIGURES 5 and 6 are inserts which may be used to provide holes of the preferred type in the resilient material covering; and

25 FIGURE 7 is a diagrammatic view, partially in elevation and partially in section, illustrating a press unit or assemblage utilizing a suction press roll of the present invention.

30 In the manufacture of paper, it is generally the practice to convey a web or sheet of paper after it is formed on a Fourdrinier wire or other sheet-forming device and which contains about 5 percent or more of water through one or more rotary presses and then through dryers for the removal of water. In the press part of a paper making machine, the web of wet paper is usually carried by the aid of one or more press felts between rotating pressure rolls for the purpose of squeezing or pressing water from the web by pressure exerted between the rolls.

35 The presses usually consist of a rotating pair of rolls, one of which may be a suction roll, that is, provided with means for removing water from the paper web by the application of a vacuum. One form of suction roll frequently employed comprises a metal roll or shell provided with a plurality of perforations which rotate past one or more suitably positioned suction boxes. The outer surface of the roll is generally covered or surfaced with a layer of a resilient material such as rubber which is provided with perforations which are in substantial alignment with the metal roll perforations so that the wet paper web conveyed between the press rolls is subject to a vacuum for removing water therefrom. Presses utilizing a suction roll, thus remove water from a wet web by means of pressure, suction and centrifugal force.

40 In the present method for manufacturing perforated rubber covered suction rolls, the metal roll or cylinder is first drilled to provide a profusion of small perforations in a predetermined pattern. These perforations may, for example, have a diameter on the order of about $\frac{3}{16}$ of an inch and widthwise centers of say, from about $\frac{15}{32}$ to about $\frac{5}{8}$ of an inch. After drilling, the outer surface or circumference of the perforated metal roll is covered with a predetermined thickness of uncured or unvulcanized rubber which is then cured to a predetermined hardness. The curing or vulcanization of the rubber also aids in the bonding of the rubber covering to the metal roll.

45 The roll may be covered with rubber having a thickness of from about $\frac{3}{8}$ of an inch to about $1\frac{1}{2}$ inches. Generally, the thickness of the rubber covering is on the order of one inch. Holes are then drilled into the hardened rubber covering to conform with the perforations in the metal roll thus resulting in thousands of small holes extending through both the rubber covering and the metal roll. The holes resulting in the rubber covering usually are of a smaller diameter than the diameter of the perforations in the metal roll. Typically, the diameter of the

holes in the rubber covering may be between about $\frac{1}{16}$ and $\frac{1}{8}$ of an inch. Upon completion of the drilling of the rubber covering, it is then ground, crowned and sanded to the desired specifications.

The above practiced method and perforated coated suction rolls produced according thereto possess several difficulties. For example, drilling through the rubber covering with steel drills and the withdrawal thereof has a tendency to disturb or weaken the bond between the rubber covering and the metal roll which may result in the separation of the covering from the roll. Obviously, separation of the covering from the roll can have several undesirable effects such as slippage of the covering which may cause misalignment of the perforations and thus appreciably reduce the removal of water by suction, or tearing of the covering so as to necessitate shutdown of the machine. Even minute separations of the covering from the roll in areas adjacent the holes are very undesirable since they provide areas where corrosion of the metal roll or shell may take place. Additionally, drilling the rubber covering results in holes having rough or burred surfaces. Such rough surfaced holes are undesirable since they are readily plugged with paper fibers trapped or retained therein by the irregular surfaces. Plugging of the holes can have several undesirable consequences such as reducing the amount of water capable of being withdrawn by suction and of being thrown off by centrifugal force. Additionally, the plugging of holes may also affect the quality of the paper if such results in the non-uniform removal of water from the web. Moreover, plugged holes necessitate costly cleaning and tend to lessen the over-all life of the covering.

In the present invention, there is provided an improved suction press roll which eliminates problems or difficulties such as mentioned above. This improved suction press roll, comprising a perforated metal roll to which is secured a resilient material such as rubber having smooth, slick surfaced holes extending radially therethrough which are in alignment with the perforations in the metal roll, is produced by covering the perforated metal roll with a predetermined thickness of a resilient material in an uncured state, curing the resilient material to a predetermined hardness in the presence of smooth surfaced inserts radially extending therethrough and into the metal roll perforations, and then removing the inserts thereby providing very desirable smooth surfaced radial holes in the resilient material. In one embodiment of the invention, the holes in the resilient material are formed by pushing or injecting smooth surfaced elongated inserts of suitable configuration or shape into the uncured resilient material so that they extend radially therethrough and into the perforations in the metal roll. After curing the resilient material to a desired hardness, the inserts are removed by suitable means to expose the holes.

The smooth surfaced holes in the resilient material can be of substantially uniform diameter throughout the length thereof or preferably, however, of irregular or nonuniform diameter by being flared at least at the inner end portion thereof. While the holes can be entirely flared preferably only a portion thereof adjacent the metal roll is so provided. The flared portion of the holes may comprise from about one-third to about one-half the total length of the holes. In one preferred embodiment, the telescope-like holes include an outer portion of substantially uniform diameter and an inner flared portion adjacent the metal roll; the diameter of the outer portion being less than the diameter of the perforations in the metal roll and the diameter of the inner portion gradually increasing inwardly from that of the outer portion to substantially that of the metal roll perforations.

Since the holes are formed through the use of smooth surfaced inserts which can be readily removed or separated from the resilient material the tendency to weaken or destroy the bond between the metal roll and the resilient material is minimized. Moreover, since the holes

are shaped or formed in a molded-like manner to a smooth surfaced insert, the surfaces thereof are also smooth and slick with little tendency for paper fibers to stick thereto. Thus, these smooth surfaced holes will not be plugged as readily as drilled holes. Smooth surfaced holes provided with a flared portion as heretofore noted are particularly advantageous since they also permit a greater amount of water to be drawn from the holes by suction and to be thrown off by centrifugal force. The greater amount of water present in the flared holes also helps to minimize the sticking of paper fibers to the sides or surfaces.

Referring now to FIGURE 1 wherein there is shown a fragmentary portion of a metal roll or cylinder 10 which is provided with a plurality or profusion of radial perforations 12 therethrough. The roll 10 can be fabricated of bronze, brass, stainless steel or other metal or alloy known in the art to be suitable. The choice of the type of metal or alloy utilized for the roll depends on the service requirements such as pressures, speeds, chemicals, etc. Likewise, the wall thickness of the roll will also depend upon the conditions of service.

The metal roll 10 is provided, usually by gang-like drilling techniques, with a myriad or profusion of holes or perforations 12 predeterminedly spaced to form a definite pattern. The pattern will depend on the type of paper or paper board machine, grades of paper or other operating conditions. The perforations 12 which radially extend completely through the wall of metal roll 10 usually are on the order of about $\frac{3}{16}$ of an inch in diameter on circumferential and spaced so that the center to center distance is on the order of between about $1\frac{5}{32}$ to about $\frac{5}{8}$ of an inch. The particular diameter of the perforations and spacing will depend upon the conditions of service.

In covering perforated metal shell or roll 10 according to the present invention, a predetermined thickness of a resilient material 14 in an uncured or unhardened state is applied in the form of a continuous sheet or sheets to the outer surface of the roll. The covering or surfacing material 14 is rubber or other polymeric material which can be applied to the roll in an uncured or unhardened condition and then cured or set by suitable treatment to produce a resilient covering of predetermined hardness. In order to allow for shrinkage and also for finish grinding to specifications, the material 14 is applied so that the thickness thereof is in excess of the finished requirements. For example, if a one inch thick covering is desired on the suction roll, the material 14 is applied or built up so as to provide a thickness of say, from about $1\frac{3}{16}$ to $1\frac{1}{2}$ inches.

After the desired thickness of uncured resilient material 14 is applied, elongated, smooth surfaced inserts or pegs 16 of desired shape or configuration are pushed radially into the material so that they extend into the perforations 12 in the metal roll 10. Generally, several inserts are first pushed through the material 14 from the inside of roll 10 in order to indicate the pattern of holes in the roll. The remaining inserts usually by gang-like techniques, are then pushed through the material 14 from the outside of the roll so that they extend into the perforations 12 in the metal roll 10. The inserts 16 are preferably sufficiently long so that they extend beyond the inner surface of the metal roll wall as well as completely through the covering of uncured material 14 and the metal roll perforations 12. The inserts which are preferably hard and rigid can be fabricated of metal, hard plastic material, wood or other material which can be provided with a smooth surface. Preferably the insert or at least the surface thereof is of a material which permits the insert to be readily released or separated from the covering after curing. For example, the inserts can comprise a steel provided with a silicone coating.

FIGURES 1, 2 and 3 illustrate inserts which can be utilized when it is desired to provide the roll covering

with circular holes having a substantially uniform diameter along the entire length thereof. As shown, in FIGURES 1 and 2, the inserts can comprise an elongated, smooth surfaced body of uniform circular cross section provided with a tapered or pointed end. The diameter of the insert will, of course, depend upon the diameter desired for holes 12. Thus, for example, when the metal roll perforations are on the order of $\frac{1}{16}$ of an inch, the insert diameter can be such so as to provide finished holes in the covering with, say, a diameter of about $\frac{1}{16}$ of an inch or $\frac{1}{8}$ of an inch. In utilizing inserts of the above configuration, they would be pushed into the covered roll so as to be substantially flush with the outer surface of the layer of uncured resilient material such as shown in FIGURE 1.

Insert 18 shown in FIGURE 3 is similar to insert 16 except that it is provided with an enlarged head portion which permits the insert to be readily removed from the outside of the roll.

After the inserts 16 are injected or inserted into place, the covering 14 is cured to a predetermined hardness. The inserts are then removed to provide the desired smooth surfaced holes in the covering of resilient material. In this embodiment, the inserts 16 produce holes having a substantially uniform diameter therethrough; these holes being aligned with the metal roll perforations. Generally, the finished holes are a smaller diameter than the diameter of the metal roll perforations.

The removal of the inserts 16 can be accomplished by suitably pushing or pulling them through to the inside of the roll 10. For instance, the inserts can be of a metal or provided with a metal portion which permits them to be drawn to the inside of the roll by magnetic means. Upon completion of the removal of the inserts, the covering can be finished ground and sanded to required specifications.

The preferred resilient material comprises rubber. In the surfacing of a perforated metal roll with such, uncured or unvulcanized rubber of a suitable thickness is applied to the roll and then after being provided with inserts vulcanized to a predetermined hardness utilizing known techniques or practices. For example, after inserts of appropriate configuration have been pushed or inserted into the green or unvulcanized rubber covering so that they extend therethrough and into the metal roll perforations, the covering is suitably wrapped with cotton or nylon wrapping to extract the air therefrom and to promote good bonding and hole formation. It should be noted that the raw or green rubber closes in about the inserts after they have been pushed therethrough and that the wrapping helps to insure that the rubber is tightly pressed or closed against the inserts. The wrapped roll is then placed in a vulcanizer or autoclave for a suitable period of time where the covering is cured or vulcanized at an elevated temperature e.g., 290° F. with either steam or hot water. After cooling and removal of the wrappings the inserts are removed to expose the desired holes.

In FIGURE 4 wherein like numbers refer to like elements of FIGURE 1, the formation of a suction press roll provided with a covering having a preferred type of telescope-like hole is shown. In this case, the inserts 20 are of a configuration so as to provide the finished holes in the covering with a flared portion adjacent the metal roll. As shown in FIGURES 4 and 5, the insert 20 can comprise an elongated smooth surfaced body including an upper portion 22 of a substantially uniform diameter, a central flared or frusto-conical portion 24 and a lower portion 26 of a substantially uniform diameter which is greater than the diameter of the upper portion 22. The lower portion is, preferably provided with a tapered or pointed end. As shown, the diameter of the central portion 24 gradually increases from that of the upper portion to that of the lower portion. A typical insert 20, for example, can comprise an upper portion of a diameter of about $\frac{1}{16}$ of an inch and a lower portion of a diameter

sufficient to just pass through metal roll perforations of a diameter of about $\frac{1}{16}$ of an inch. The lower portion can thus be of a diameter of about $\frac{5}{32}$ of an inch. The diameter of the central portion 24 in this case will gradually increase from that of the upper portion, that is $\frac{1}{16}$ of an inch, to that of the lower portion, that is, $\frac{5}{32}$ of an inch.

In utilizing inserts 20, they are pushed or inserted into the covered roll so that the central flared portion is positioned in the portion of the covering adjacent the metal roll. The removal of the inserts 20 can be accomplished by suitably pushing or pulling them through to the inside of the roll 10.

In FIGURE 6 there is shown another type of insert which can be utilized in forming flared holes in the covering. As illustrated, this insert 30 comprises an elongated smooth surfaced body of a generally frusto-conical configuration. Preferably this body is provided with a tapered or pointed end to facilitate the insertion thereof into the covering. Inserts of this configuration provide holes which are flared throughout, that is, the diameter of the holes gradually increases inwardly from the outer surface of the covering to the inner surface thereof.

Referring now to FIGURE 7, there is shown a press assemblage utilizing a suction roll of the preferred construction for the removal of water from a wet paper web. After a water laden paper web or sheet 40 is formed, for example, in the Fourdrinier, it is conveyed at a high speed by one or more porous press belts 42, generally of felt between the nip 44 of an upper roll 46 and a lower suction press roll 48 in order to press or squeeze water from the paper web 40. The upper press roll 46 can be of well-known construction but preferably comprises a hollow roll of sintered metal having a predetermined porosity which is provided with means for heating it at least in the area of and adjacent the nip. Preferably, the sintered roll is provided with means for supplying a hot gas under pressure thereto so as to heat it and to provide a flow of hot gas therethrough. Upper press rolls of the desired construction are more fully discussed in my U.S. Patent No. 3,162,568.

The lower suction press roll 48 is shown as comprising a rotatable metal cylinder or shell 50 having perforations 52 extending radially therethrough. Secured to the outer surface of cylinder 50 is a layer of resilient rubber 54 having smooth surfaced holes 56 radially extending therethrough and in alignment with the cylinder perforations 52. The holes 56 in the rubber covering or layer 54 comprise an outer portion 58 of substantially uniform diameter and an inner flared portion 60 the diameter of which gradually increases inwardly from that of the outer portion 58 to substantially that of the perforations 52 in the metal cylinder 50. A suction box 62 is mounted within the cylinder 50 to define a localized suction in the area of the pressure nip 44. As the rapidly moving felt 42 and paper web 40 pass through the nip 44, water is pressed and sucked therefrom into holes 56. Some of the water in holes 56 is withdrawn through holes 52 by means of suction and some is thrown or spewed out by centrifugal force. The removal of water from the paper web is thus achieved through a combination of pressure, suction and centrifugal force.

The provision of smooth surfaced flared holes in the suction roll cover such as holes 56 above is particularly desirable since they permit greater water removal. Moreover, such holes are not readily plugged or clogged and thus there is little or no interference with the suction action. Furthermore, such holes can be easily and readily cleaned such as by blowing air therethrough or by being treated or washed with an aqueous solution containing a cleansing agent, e.g., a soap or detergent.

Since the preferred flared holes have a greater volume, they provide a greater reservoir of water to be drawn therefrom by suction and to be thrown out by centrifugal force. Additionally, the greater amount of water present in the holes tends to minimize the sticking of paper fibers to the surfaces or sides thereof thus preventing

plugging and permitting maximum suction and centrifugal force action or efficiency.

Furthermore the smooth surfaced holes of the present invention have little tendency for paper fibers to stick thereto and thus plugging of the holes is minimized. The smooth hole surfaces also permit the maximum amount of water to be withdrawn by the pull of the vacuum and to be thrown off by centrifugal force.

It should also be noted that the present method for forming the smooth surfaced holes in the covering does not disturb the bond between the covering of resilient material and the metal roll and thus problems resulting from a loose or partially separated covering are avoided. It should also be pointed out that the present suction rolls can be incorporated into equipment now in use and thus does not require the designing and purchasing of new equipment.

Although the improved suction press rolls have been described in connection with a paper making machine, it should be pointed out that such suction rolls are also applicable to other machines such as of the type used, for example, in the manufacture of asbestos or asbestos-cement products.

Since certain changes may be made in the above apparatus and method without departing from the scope of the invention herein involved, it is intended that all matter contained in the above description or shown in the accompanying drawings shall be interpreted as illustrative and not in a limiting sense.

What is claimed is:

1. A suction press roll comprising a perforated metal

roll to which is secured a resilient material having smooth surfaced holes which extend radially therethrough and which are in alignment with the perforations in the metal roll, at least the inner end portion of said holes being flared.

2. A suction press roll comprising a perforated metal roll to which is secured a rubber covering having smooth surfaced circular holes which extend radially therethrough and which are in alignment with the perforations in the metal roll, said holes consisting of an outer portion of substantially uniform diameter and an inner flared portion adjacent said metal roll, the diameter of said outer portion being less than the diameter of said perforations in said metal roll, and the diameter of said inner flared portion gradually increasing inwardly from that of said outer portion to substantially the diameter of said perforations in said metal roll.

3. A suction press roll according to claim 2 wherein said inner flared portion comprises from about one-third to about one-half the total length of said holes.
